198,978

DOLL OR SIMILAR ARTICLE

Avis R. Rossi, Southboro, Mass., assignor to Constance B. Brewer, Chestnut Hill, Mass.

Filed Apr. 17, 1964, Ser. No. 79,555

Term of patent 14 years

(Cl. D34—2)

FIG. 1 is a front elevational view of a doll embodying my new design;

FIG. 2 is a side elevational view looking from left to right at the doll shown in FIG. 1; and

FIG. 3 is a rear elevational view of the doll shown in FIG. 1.

I claim:

The ornamental design for a doll or similar article, substantially as shown.
